FIGURE 1 is a perspective view showing the front and side of a combined hamper and seat embodying my new design;

FIGURE 2 is a top plan view of the combined hamper and seat shown in FIGURE 1;

FIGURE 3 is a rear elevational view of the combined hamper and seat shown in FIGURES 1 and 2;

FIGURE 4 is a side elevational view of the combined hamper and seat shown in FIGURES 1, 2 and 3; and

FIGURE 5 is a front elevational view of the hamper seat shown in FIGURES 1, 2, 3 and 4.

The appearance of the side of the chair not shown is a mirror image of the side shown.

I claim:

The ornamental design for a combined hamper and seat, substantially as shown and described.
